UNITED STATES PATENT OFFICE.

HARLAN S. RECTOR, OF CHICAGO, ILLINOIS, ASSIGNOR TO THE BECKLEY-RALSTON CO.,
OF CHICAGO, ILLINOIS, A CORPORATION OF ILLINOIS.

DESIGN FOR A TIRE CASING.

Application filed December 15, 1921. Serial No. 522,712. Term of patent 3½ years.

To all whom it may concern:

Be it known that I, HARLAN S. RECTOR, a citizen of the United States, residing at Chicago, in the county of Cook and State of Illinois, have invented a new, original, and ornamental Design for Tire Casings, of which the following is a specification, reference being had to the accompanying drawing, forming part thereof.

The figure is a perspective of a section of a tire embodying the new design.

I claim:

The ornamental design for a tire casing, as shown.

HARLAN S. RECTOR.
